UNITED STATES PATENT OFFICE.

HENRY ST. PIERRE, OF WORCESTER, MASSACHUSETTS, ASSIGNOR TO ST. PIERRE CHAIN CORPORATION, OF WORCESTER, MASSACHUSETTS, A CORPORATION OF MASSACHUSETTS.

CHAIN TOOL.

Application filed September 3, 1926. Serial No. 133,499.

This invention relates to a tool used for opening and closing links of cross chains particularly, although capable of performing similar operations on other chains and in 5 other places.

The principal objects of the invention are to provide a strong and durable tool efficient for opening and closing links of all sizes, provided with means for gripping the links so 10 that they cannot slip, having no operating surfaces that project out in the way where they are likely to get broken and having a material advantage in leverage over the tools now on the market.

15 Another object of the invention is to provide handle levers in duplicate form so that they can be made in a single set of dies.

Other objects and advantages of the invention will appear hereinafter.

20 Reference is to be had to the accompanying drawings in which

Fig. 1 is a side view of a chain tool constructed in accordance with this invention and shown closed;

25 Fig. 2 is an edge view of the same;

Fig. 3 is an end view of the jaws;

Fig. 4 is a view similar to Fig. 1, enlarged and showing the jaws open just commencing the closing operation on a small link;

30 Fig. 5 is a perspective view of the tool shown as used for closing a large link, one wire at a time; and

Fig. 6 is a similar view showing the tool in use for opening a link.

35 The tool is made up of two pairs of elements. The handles or operating levers 10 are formed by forgings and arranged to be pivoted together on a stud 11. They are re-forged exactly alike and turned over or re-

40 versed to bring them into the position shown. Each one is provided with a projecting arm 12 in alignment substantially with the handle and located beyond the pivot stud. It will be noticed that this arm is very short

45 while the operating arm is very long. This gives an extremely advantageous leverage.

The other pair of elements are jaw levers 13. These also are pivoted on a pivot stud 14. Each one has a long arm which is pivoted to the short end of one of the arms 12 by a pivot stud 15. This arm preferably is longer than the jaw 16 which is located on the other side of the stud 14. Therefore there is a further increase in leverage here so that I

get a powerful leverage. The pivot studs 11 55 and 14 are spaced apart and parallel, with the terminal edges of the jaws 16 and of the bills 17.

The opening bills 17 when in closed position as shown in Fig. 1, pass each other, each 60 having a curved surface fitting the adjacent surface of the other and concentric with the pivot stud 14. The jaws 16 are designed not to come into meeting contact at all. They are simply angular projections located at the sides 65 of the bills 17 and having straight parallel V-shaped ends for engaging both wires or one wire at the time and closing a link as shown in Figs. 4 and 5 respectively. They are located in convenient position at the side of the 70 bills 17 which are used in opening the links as indicated in Fig. 6. They are sharp enough to nick the link and grip it firmly so that it will not slip or tilt.

In the use of the device the old link is 75 opened in the way that is common in this line by forcing the bills 17 in between the turned over ends of the hook or link as shown in Fig. 6. For closing a large link, as in Fig. 5, one end of the link is forced inwardly by 80 the jaws 16 in the position shown. Then the tool is turned over and the other side forced down against the long bar of the link. Small links can be closed by one motion with the same tool as shown in Fig. 4. The bills 17 85 have side faces parallel with the planes of their movement which afford guiding surfaces for the links and hold them against tilting. This constitutes a compact tool having a very advantageous leverage and 90 the two handles are made in the same dies and turned over to make them rights and lefts. This reduces the cost of manufacture and simplifies the construction and also reduces the cost of repairs.

95 This has been found in practice to be a very powerful, durable and strong chain tool not requiring the exercise of much power on the part of the operator to open and close large chain links. The heads of the jaws 100 are thick and heavy and the whole structure is very strong and durable.

Although I have illustrated and described only a single form of the invention I am aware of the fact that modifications can be 105 made therein by any person skilled in the art without departing from the scope of the invention as expressed in the claims. There-

fore, I do not wish to be limited to all the details of construction herein shown and described, but what I do claim is:—

- 5 1. A chain tool comprising a pair of jaw members pivoted together, each having a link separating bill and a link closing jaw parallel with each other across the jaw member and in juxtaposition, the closing jaws having edges remaining far apart when the jaws are closed as far as possible, said separating bills having side faces parallel with their planes of movement and affording guiding surfaces for the chain link to be opened.
- 10 15. 2. A chain tool comprising a pair of jaw members having a pair of bills having edges for separating links and sides affording guiding surfaces and having adjacent thereto a pair of closing jaws separated from each other when closed as far as possible, said closing jaws having opposite edges parallel with the edges of the bills for engaging and gripping the outer surfaces of the link and holding the same against slipping.
- 20 25. 3. A chain tool comprising a pair of jaw members, each member having a link separating bill terminating in an edge and a link closing jaw parallel with each other across the jaw member and in juxtaposition, the closing jaws having V-shaped edges and parallel with the edges of the bills for preventing the slipping of the link.
- 30 35. 4. A chain tool comprising a pair of jaw members each having a link separating bill and a link closing jaw, each having edges of a material length parallel with each other across the jaw member, each bill being in juxtaposition with the jaw on the same jaw member, the closing jaws being located di-

rectly on the sides of the bills and the jaw members being pivoted together on an axis parallel to said edges, the sides of the separating bills being parallel to their planes of motion and affording guiding surfaces.

5 40. 5. A chain tool comprising a pair of jaw members each having a link separating bill and a link closing jaw parallel with each other across the jaw member and in juxtaposition, the bills having terminal edges, the closing jaws being located directly on the 45 sides of the bills, having edges, and being pivoted together on an axis parallel to their edges and the bills closing past each other on the arc of a circle drawn from the pivot as a center and having sides parallel with their 50 plane of movement and affording guiding surfaces.

6 55. 6. A chain tool comprising a pair of jaw members each having a link separating bill and a link closing jaw, each having edges 60 parallel with each other across the jaw member, the closing jaws consisting of edges transverse to the plane of movement for preventing the slipping of the link, being pivoted together and incapable of being closed 65 entirely together.

7 70. 7. A chain tool comprising a pair of jaw members each having a link separating bill and a link closing jaw, each having a transverse edge parallel with the other across 75 the jaw member and located adjacent to each other, the closing jaws having edges located in a position to remain far apart when they are in their limiting closed position.

In testimony whereof I have hereunto affixed my signature.

HENRY ST. PIERRE.
